UNITED STATES PATENT OFFICE.

BUTLER BAKER, OF HAYMARKET, VIRGINIA.

CLOTHES FORM.

Application filed August 25, 1925. Serial No. 52,343.

The invention relates to clothes forms and has for its object to provide a device of this character comprising a plurality of annular members connected together by flexible members and adapted to be interposed between the clothing of a person and the body for maintaining the clothing spaced from the body, particularly in warm weather for preventing the objectionable features of clothing sticking to the body.

A further object is to provide a garment form comprising body and arm sections suspended from shoulder straps and a trouser section detachably connected to the lower end of the body section, thereby allowing either or both sections to be used as desired.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

Referring to the drawing, wherein a single figure shows a perspective view of the form the numeral 1 designates a plurality of horizontally disposed flexible rings adapted to encircle the body of the wearer under the clothing, and 2 a plurality of vertically disposed pliable connecting members, which connect the rings 1 together and at the same time allow bending of the body, without binding. Secured to the upper ring 1 are shoulder straps 3, which straps arch the shoulders of the wearer and have connected thereto outwardly extending flexible members 4 to which annular members 5 are secured, and which annular members form sleeve forms for maintaining the sleeves of a garment spaced from the body of the wearer.

Detachable connected by means of downwardly extending straps 6 carried by the lower ring 1 is an annular member 7 adapted to encircle the hips of the wearer and main-

tain the upper portion of the trousers spaced from the body. Depending from the annular member 7 are leg sections formed from a plurality of horizontally disposed annular members 8, which annular members are supported by means of downwardly extending flexible members 9 carried by opposite sides of the annular member 7 and by a U-shaped flexible member 10, the arms of which are connected to the inner sides of the annular members 8, therefore it will be seen that leg forms are provided which will maintain the legs of a garment spaced from the legs of the wearer at all times.

From the above it will be seen that a garment form is provided which will maintain clothing spaced from the body of the wearer at all times, thereby overcoming the disagreeable feature of the clothing sticking to the body during warm weather, and that the device is simple in construction, light and constructed in a manner whereby it will not interfere with the bending of the body. It will also be seen that the pants section may be easily detached from the upper section, thereby allowing either or both sections of the form to be used as desired.

The invention having been set forth what is claimed as new and useful is:—

A garment form of the character described, and comprising a body section, a pants section detachably connected thereto, said body section and pants section being formed from a plurality of horizontally disposed annular members, flexible connections between the annular members, shoulder straps carried by the upper annular member, sleeve sections, said sleeve sections comprising a plurality of spaced annular members and flexible members connecting the shoulder straps and the sleeve section annular members all of said sleeve flexible members being in the same vertical plane.

In testimony whereof I have signed my name to this specification.

BUTLER BAKER.
